his Attorney.

UNITED STATES PATENT OFFICE.

HENRY LURZ, OF JERSEY CITY, NEW JERSEY.

KITE.

1,265,797.

Specification of Letters Patent. Patented May 14, 1918.

Application filed July 25, 1917. Serial No. 182,619.

To all whom it may concern:

Be it known that I, HENRY LURZ, a citizen of the United States, and a resident of Jersey City, in the county of Hudson and State of New Jersey, have invented certain new and useful Improvements in Kites, of which the following is a specification.

This invention relates to kites and particularly to certain improvements in the corners thereof. The object of my improvements is to provide corners of greater strength and wearing qualities than heretofore.

With this object in view and others which will appear later herein, my improvements comprise features and combinations of features illustrated in their preferred embodiment in the drawing accompanying this specification, wherein—

Figure 1 is a front elevation showing one corner of a kite embodying my improvements, with the several members in assembling position. Fig. 2 is a similar view showing a further step in said assembling. Fig. 3 is a plan view, partly in section, taken on line 3—3 of Fig. 2. Fig. 4 is a view similar to those of Figs. 1 and 2, showing the completed assembly. Fig. 5 is a view similar to that of Fig. 1 and showing a modification of my improvements. Fig. 6 is a front elevation similar to that of Fig. 5 and showing the several members assembled.

The corners of a kite are particularly subject to strain and ill-usage, and in the ordinary type the corners are usually broken before any other portions of the kite, and the usefulness and efficiency of the toy materially decreased or destroyed. With my improvements the life and efficiency of the kite are greatly increased.

My improvements include a patch or reinforcing member, preferably of fabric or other sufficiently strong sheet material, of approximately I shape. Said patch or reinforcing member 2 comprises a neck 4, a head portion having laterally extending arms 5 and 6 respectively, and a body portion preferably having wider laterally extending arms 7 and 8 respectively. Said upper arms are inclined upwardly and said lower arms are inclined downwardly, to correspond with the particular angularity of the kite corner in which said patch is employed.

In placing patch 2 in position on the kite body 10, and which body may be of paper

or other suitable sheet material, I locate the medial lines of lower arms 7 and 8 over the lines respectively on which flaps 11 and 12 of said kite body 10 are to be folded, and by a suitable adhesive applied over the whole of the underside of arms 7 and 8 and the lower mid-portion of the patch adjoining said arms, secure said patch in place. Then if desired, cord 9 may be laid in place along the lines of fold, all as shown in Fig. 1. Next, former 13, of slightly greater width and thickness than that of the kite stick to be used, is placed in position, as shown in Fig. 2. Adhesive, as gum, is then applied to the upper faces respectively of arms 5 and 6, and the upper portion of patch 2 is folded downwardly over former 13 and said gummed arms are pressed against the lower portions, below cord 9, of the exposed faces of arms 7 and 8 respectively, said arms 5 and 6 being tucked in closely against former 13, Fig. 3, thereby forming a pocket 14 about the head of said former, the mid-portion of string 9 passing through the head of said pocket. Then gum is applied to the exposed portions of flaps 11 and 12 of the kite body, and to the upper portions, above cord 9, of arms 7 and 8, Fig. 2, and said flaps and arms folded over onto the lower portions of said arms and onto the body of the kite.

It will be observed that arms 5 and 6 are slightly narrower than corresponding portions of arms 7 and 8 to which they are gummed, so that when the upper portions of arms 7 and 8 are folded over and gummed down they overlap said arms 5 and 6 and contact respectively with their own lower portions, thus affording a very secure hold for arms 5 and 6. Also flaps 11 and 12 of body 10 have, in Fig. 1, exposed portions respectively, above arms 7 and 8, whereby when they are folded over onto the body of the kite, they contact with and are gummed to said body below the lower folded edges of arms 7 and 8, thus affording a secure hold for all the elements inclosed within. There are thus provided a reinforced corner for the kite and a pocket 14 for the end of a kite stick, both features adding materially to the durability and efficiency of the kite. Furthermore the combination of pocket 14 and cord 9 therein precludes the necessity of the usual slot in the stick end for receiving and holding the string, as said pocket so holds the string in posi-

tion as to always present it for engagement by the stick end when that stick end is thrust into said pocket.

In the modification of Figs. 5 and 6, patch 5 2 is formed integral with kite body 10. This modification is particularly efficient when kite body 10 is formed from cloth, and when so formed cord 9 may be omitted if desired. In this modification the upper 10 arms 5 and 6 having been previously gummed are folded over and down onto the kite body, about former 13, as already described in connection with Figs. 1 to 4 inclusive. Then gummed flaps 11 and 12 are 15 folded over and down onto said arms and kite body, as shown in Fig. 6, thereby securing the several elements together and forming a reinforced corner and a pocket for the kite stick end.

20 I claim:

1. In a kite the combination of a body of sheet material, a reinforcing member of sheet material comprising a body portion and a head portion, said head portion being 25 provided with oppositely extending arms and said head portion being adapted for folding down over said body portion, and means for securing said arms and body to said kite body whereby a pocket is provided 30 for the end of a kite stick.

2. In a kite the combination of a body of sheet material having edge flaps, and a reinforcing member folded over onto said body, said body edge flaps being adapted to 35 be folded over said reinforcing member and secured thereto, whereby a pocket is provided for the end of a kite stick and the edges of the kite adjacent said pocket are reinforced.

40 3. In a kite the combination of a body of sheet material, a reinforcing member of sheet material comprising a neck, upper laterally extending arms and lower laterally extending arms, said lower arms being wider 45 than said upper arms respectively and adapted to inclose said upper arms when said upper arms are folded over onto said lower arms and said lower arms folded onto themselves respectively, means for securing said 50 folded portions together, and means for securing said reinforcing member to the kite body.

4. In a kite the combination of a body of sheet material, a reinforcing member of 55 sheet material comprising a neck, two opposite upper laterally extending arms and two opposite lower laterally extending arms, said lower arms being more than twice the width of said upper arms respectively, so 60 that when said upper arms are folded over onto said lower arms and said lower arms folded over onto themselves respectively, said lower arms will overhang said upper arms and present contacting surfaces with 65 themselves respectively, means for securing

said folded portions together, and means for securing said reinforcing member to the kite body.

5. In a kite the combination of a body of sheet material having edge flaps, a reinforcing member of sheet material comprising a neck, two opposite upper laterally extending arms and two opposite lower laterally extending arms, said lower arms being more than twice the width of said upper arms 70 respectively, so that when said upper arms are folded over onto said lower arms and said lower arms folded over onto themselves respectively, said lower arms will overhang said upper arms and present contacting surfaces with themselves respectively, said body edge flaps being of sufficient width when folded over said folded arms of the reinforcing member to overhang said arms and contact with the body of the kite, means 75 for securing said folded portions together, means for securing said reinforcing member to the kite body, and means for securing said flaps to said arms and to the kite body.

6. In a kite the combination of a body of sheet material having edge flaps, a reinforcing member folded over onto said body, said body edge flaps being adapted to be folded over said reinforcing member and secured thereto, whereby a pocket is provided for 80 the end of a kite stick and the edges of the kite adjacent said pocket are reinforced, and a cord within the folds of said body flaps, said cord passing through the upper portion of said pocket and adapted to be 85 engaged by the end of said kite stick.

7. In a kite the combination of a body of sheet material, and a reinforcing member of sheet material comprising a neck, upper laterally extending arms and lower laterally 90 extending arms, said lower arms being wider than said upper arms respectively and adapted to inclose said upper arms when said upper arms are folded over onto said lower arms and said lower arms folded onto themselves respectively.

8. In a kite the combination of a body of sheet material, a reinforcing member of sheet material comprising a neck, upper laterally extending arms and lower laterally 95 extending arms, said lower arms being wider than said upper arms respectively and adapted to inclose said upper arms when said upper arms are folded over onto said lower arms and said lower arms folded onto themselves respectively, whereby a pocket is provided for the end of a kite stick and the edges of the kite adjacent said pocket are reinforced.

9. In a kite the combination of a body of sheet material having edge flaps, a reinforcing member of sheet material comprising a body portion and a head portion, said head portion being provided with oppositely extending arms and said head portion being 100

adapted for folding down over said body portion, means for securing said arms and body to said kite body, and means for securing said flaps to the reinforcing member and to the kite body whereby a pocket is provided for the end of a kite stick and the edges of the kite adjacent said pocket are reinforced.

Signed at New York, borough of Manhattan, in the county of New York and State of New York, this 23d day of July, 1917, before two subscribing witnesses.

HENRY LURZ.
